ATTORNEY.

UNITED STATES PATENT OFFICE.

HENRY J. BERTHOLD, OF IRVINGTON, NEW JERSEY.

SPARK-PLUG.

1,143,026.

Specification of Letters Patent. Patented June 15, 1915.

Application filed June 18, 1912. Serial No. 704,283.

To all whom it may concern:

Be it known that I, HENRY J. BERTHOLD, a citizen of the United States, residing at Irvington, in the county of Essex and State of New Jersey, have invented certain Improvements in Spark-Plugs, of which the following is a specification.

The objects of this invention are to provide in a spark plug a binding post of simple and inexpensive construction which cannot work loose and become inefficient by repeated screwing on and off of the binding screw which clamps the circuit wire; to prevent the leakage of gas around the central pin or electrode of the spark plug; to secure a tight firm seating of the porcelain in its bushing and of said bushing in the shell, so as to prevent leakage and looseness; to provide a spark plug which can be readily taken apart for cleaning or the like; to provide readily adjustable means whereby the spark gap between the electrodes may be regulated; to provide a plurality of paths for the spark to span said gap; to secure simplicity of construction and economy of manufacture, and to obtain other advantages and results as may be brought out in the following description.

Referring to the accompanying drawings, in which like numerals of reference indicate the same parts throughout the several views, Figure 1 is a view in elevation of my improved spark plug; Fig. 2 is a longitudinal sectional view of the same applied, and on larger scale; Fig. 3 is a cross-sectional view on line A—A of Fig. 2; Fig. 4 is a cross-sectional view on line B—B of Fig. 2, and Fig. 5 is a perspective view of the bridge or gap plate.

In the specific embodiment of the invention illustrated in said drawings, 1 indicates the cylinder wall of an internal combustion engine into which the shell 2 is secured by means of exterior threads 3 at its lower end, said end being reduced diametrically to provide an annular shoulder 4 above the same which rests against an asbestos gasket or other packing 5 between the said shoulder 4 and the wall 1, so that an imperious joint is provided thereat. Above the said shoulder 4 is an exteriorly angular portion 6 to which a wrench or other suitable tool may be applied to insert or remove the said shell 2 with respect to the cylinder, as mentioned.

The shell 2 is longitudinally chambered

or bored, as at 7, the diameter of its chamber increasing, as at 8, at the outer or wrench-receiving end of the shell. The wall of this increased bore or chamber is preferably a frustated conical surface flaring outward and having threads 9 cut into said conical surface, so that a bushing 10, exteriorly tapered and threaded to correspond, may be screwed into or out of the shell 2. By cutting the threads upon frustated conical surfaces as described, the resistance to shear is kept high and a tight joint is obtained to prevent the passage of gas when the parts are operatively assembled, and at the same time only a mere start or partial rotation of one part with respect to the other is required to loosen them sufficiently to be readily separated by hand. In order to supply a grip for a wrench, the bushing 10 has an angular portion 11 beyond its said threads 12, as shown. Said bushing 10 furthermore provides an interior conical or tapering surface, the smaller end of which is at the outer or wrench-receiving end of the bushing, said surface being adapted to wedgingly engage the correspondingly tapered outer surface 13 of a porcelain or other insulating member 14 inserted in the bushing, and held said porcelain tightly and firmly. Inward displacement of the porcelain 14 is prevented by inwardly curling or crimping over against an appropriate shoulder 15 of the insulating member, as at 17, a reduced or thinned collar 18 projecting originally from the inner end of the bushing 10 and preferably being an integral part thereof. In manufacture, the engaging and tapering surfaces of the porcelain and bushing are ground or machined and the two parts then forced firmly together and clamped in such relation by the crimped collar 18 as described. This provides a perfectly imperious joint to the passage of the gases, and a structure which it can readily be seen is free from any possibility of the porcelain 14 being blown out by the pressure of gases caused by the explosions within the cylinder.

The upper or outer end 19 of the porcelain 14 is shaped or made angular in cross-section, here shown as hexagonal, and is provided inwardly beyond said angular end 19 with a shoulder 20 facing away from said end 19 and which I have shown as formed by cutting an annular groove 21 into and around said porcelain 14, although it might be formed in any other way mechanical skill

may suggest. Superimposed upon the said hexagonal upper or outer end 19 of the porcelain 14, is a hexagonal plate 22 having integrally formed with itself an upwardly projecting threaded binding post 23. A washer or packing 24, of asbestos or other preferably heat-proof material, is inserted between the said end 19 and plate 22, and said plate 22 and the packing 24 are firmly held and 10 clamped in this relation and position by a cap 25 hexagonal in cross-section to fit the end 19 and apertured to permit the binding post 23 to protrude therethrough. The lower edges of said cap are curled or 15 crimped, as at 41, under the said shoulder 20 in the porcelain 14, and this not only prevents lateral displacement of the plate 22 and its binding post 23, but, by virtue of the hexagonal shape of cap 25, plate 22 and 20 the upper end 19 of the insulating member over which the cap fits, also prevents angular rotation or twisting of the plate and binding post. The construction of the plate 22 and the cap 25 in two separate pieces conduces to 25 ease and economy of manufacture, and the hexagonal or other angular shape avoids the use of cement or other adhesives ordinarily relied upon to keep the binding post from twisting.

30 Extending longitudinally through the binding post and out of the lower end of the porcelain 14, is a central pin or electrode 26, which is entirely free electrically from the shell 2 or other parts electrically connected thereto, and projects therebeyond into the cylinder of the engine. At diametrically opposite points of the inner edge of the shell 2, slots are cut into said shell to receive the ends 27, 27 of a bridge or gap plate 28 35 spanning the opening of said sleeve. From the ends 27 the bridge 28 is inclined or bent away from the shell, as at 29, 29, and then extends for its middle portion 30 parallel to the ends 27, 27, so that said middle portion is spaced from the end of the shell, as shown. A transverse slot 31 and a longitudinal slot 32 intersect at the center of said middle portion 30 of the bridge, and provide thereby 40 points 33, which are bent upwardly or toward the shell 2, as shown, and form a series of terminals of the second or co-acting electrode. The pin 26 forming the first electrode passes between the points 33 of the bridge without touching them, and thus a plurality of spark gaps are provided around the pin 26.

45 By virtue of the slots 31 and 32, and more especially the longitudinal slot 32, the said points 33 may be squeezed together or spread apart at will to regulate the gap or distance of them from the pin 26, and thus adjustability is secured. The arrangement of the points 33, as thus set forth, affords a plurality of possible sparking points, which is desirable in case one point should become 50 broken, worn or coated. The points being bent out of the general plane of the central portion 30 of the bridge are protected more efficiently from the oil and other particles pervading the cylinder chamber when in use, 70 and yet are within said chamber to be in contact with the explosive gases to ignite them when the spark passes. Obviously, by their upwardly projecting position, as shown, the said points 33 will always keep 75 clean and clear of oil or the like, which will tend to run downwardly off said points. It will be understood that one wire from the source of electric energy is connected to the engine, which, being a conductor, transmits 80 the electric energy to the bridge 28, and the other wire is connected by the clamping action of a nut 35 to the binding post 23 which is electrically joined to the central pin or electrode 26.

85 Preferably the ends of the bridge 28 are held in their slots in the shell by "staking" or pressing the metal at the edges of the slots over the said ends slightly.

Having thus described the invention, what I claim is:

1. In a spark plug, an insulating member having an end angular in cross section, a binding post having an angular base plate adapted to seat on said end, and a correspondingly angular cap adapted to inclose said plate and end of the insulating member.
2. In a spark plug, an insulating member having a central passage and provided with an end angular in cross section, an electrode 100 in said passage, a binding post having an angular base plate, said binding post being bored to receive said electrode, and a correspondingly angular cap adapted to be slipped over said angular base plate and over said angular end of the insulating member securing said binding post nonrotatively with respect to the insulating member.
3. In a spark plug, an insulating member having an end angular in cross-section, a binding post having an angular base plate adapted to seat on said end, a correspondingly angular cap inclosing said base plate and end of the insulating member, and means for retaining said cap against removal.
4. In a spark plug, an insulating member having an end angular in cross section and provided with a peripheral shoulder adjacent said angular end, a binding post having an angular base plate adapted to abut against said end of the insulating member, and a correspondingly angular cap inclosing said base plate and end and having its edges bent over said shoulder.
5. In a spark plug, a shell adapted to be mounted in the wall of a cylinder, a central electrode for said shell projecting from the inner open end thereof, and a bridge at the end of said shell having a middle portion 110

surrounding said electrode and arms projecting from said middle portion and secured to the shell, said bridge having radial slots extending from its central opening through said middle portion into the said arms, whereby the parts of the middle portion between said slots may be bent toward and away from each other.

6. In a spark plug, a shell adapted to be mounted in the wall of a cylinder, a central electrode for said shell projecting from the inner open end thereof, and a bridge at the end of said shell having a middle portion surrounding said electrode at a distance from the shell and arms projecting from said middle portion bent toward the shell and secured thereto, said bridge having ra-

dial slots extending from its central opening through said middle portion into the said arms, whereby the parts of the middle portion between said slots may be spread apart and pressed together.

7. In a spark plug, an insulating member having an end angular in cross-section, a conductor supported by the insulating member having an angular portion adjacent said end, and a correspondingly angular cap engaging said angular portions of the conductor and of the insulating member.

HENRY J. BERTHOLD.
